UNITED STATES PATENT OFFICE

2,471,106

VALVE CLEARANCE GAUGE

Clarence E. Hall, Portland, Oreg.

Application June 28, 1945, Serial No. 602,045

4 Claims. (Cl. 33—181)

1

This invention relates to valve clearance gauges and is particularly adapted to be used in connection with Ford V-8 motors.

The primary object of the invention is to determine the length of valve lifters to be used after the valves have been reconditioned. Heretofore the valves were inserted in their position and thickness gauges were used between the lifters and the valve stems. This required the trying of a number of lifters which consumed time and effort, but with my new and improved valve clearance gauge it takes but a moment to determine the length of lifter and the lifter can be selected from the supply box and inserted within its guide, completing the operation.

These and other incidental objects will be apparent in the drawings, specification and claims.

Referring to the drawings:

Figure 1 is a fragmentary sectional view of a Ford motor block, illustrating the valve assembly.

Figure 2 is a fragmentary view similar to Figure 1 with the exception that the valve assembly is removed and my new and improved clearance gauge is shown in place for determining the length of the valve lifter to be used.

Figure 3 is a fragmentary sectional view, taken on line 3—3 of Figure 2, looking in the direction indicated, parts of my valve clearance gauge being broken away for convenience of illustration.

Figure 4 is a fragmentary sectional view of the tip of the gauge used to contact the cam shaft, parts broken away for convenience of illustration.

In the drawings:

A standard motor block is indicated at 1, having the usual cam shaft 2 and valve assembly 3 mounted therein. The valve proper is indicated by numeral 4, operating within the regular valve guides 5, the stem 6 terminating in the enlarged end 7, which is operated by the valve lifter 8 riding upon the cam 9. The valve 4 is shown resting on the valve seat 10, and when this seat is reamed out and ground, together with the face 11 of the valve, the stem 6 will be lowered bringing the face 7 of the stem closer to the face 12 of the lifter 8, thereby requiring that another lifter be used providing the proper clearance at 13, which is specified by the manufacturer. Heretofore these valve lifters were inserted within their guides 14 and the valve stem ground down until the proper clearance 13 was provided, this of course required considerable time.

I will now describe the construction of my new and improved valve clearance gauge. The gauge consists of a hollow body portion 15 having a hollow stem 16. Slidably mounted within the

2

stem 16 is a rod 17 which passes through the bearing 18 at its upper end and has an enlarged collar 19 at its lower end. The purpose of the collar 19 is to provide a shoulder 20 upon which the spring 21 rests at its lower end, having its upper end contacting the shoulder 22.

The shoulder 23 of the collar 19 rests upon an adjusting sleeve 24 and is maintained thereagainst by the spring 21. An adjusting screw 25 is threaded within the end 26 of the shaft 17 and is locked relative thereto by the locking nut 27, the purpose of which is to adapt the gauge to various types of motors. A standard gauge 28 is threaded and locked to the upper end 29 of the shaft 17, the face of which can be read through the opening 30 of the tool. The usual gauge plunger 31 extends upwardly from the gauge 28. A valve seat 32 is formed within the upper end of the tool and this seat is formed in a separate sleeve 33, which is interchangeable for meeting the different types of motor valve assemblies.

I will now describe the operation of my new and improved valve clearance gauge. The complete valve assembly 3 is first removed from the motor. The stem 16 of the tool is inserted through the valve guide opening within the block, the end 34 of the adjusting screw 25 resting upon the cam 9. This will raise the stem 17 together with the gauge 28 to a certain predetermined position which has been determined by the manufacture of the gauge to correspond with a standard valve clearance of a new motor. The valve 4 is dropped into the upper end of the gauge, best shown in Figures 2 and 3, its lower end 7 coming to rest on the plunger 31. The valve is forced down upon the seat 32 and against the plunger, causing the indicator hand 35 of the gauge to come to rest on a given indicated numeral on the face of the dial 36. This numeral will correspond to the number stamped on the valve lifters 8 and will indicate the lifter to be used in connection with the valve 4, whose face 11 has been reconditioned together with the seat 10 of the block.

It can be readily understood that when the seat 10 of the block has been reground or refaced it will allow the gauge tool to drop a little lower in the motor block. It can also be understood that when the face of the valve 4 has been reground that the valve will drop a little lower in the gauge body. This of course causes the stem of the valve to force the hand of the gauge further around, indicating that a shorter valve lifter must be used and it will indicate on the gauge the exact length of this lifter to be selected, thereby carrying out the object of my invention.

I do not wish to be limited to the exact mechanical structure, as I have illustrated, as other mechanical equivalents may be substituted still coming within the scope of my claims.

What I claim as new is:

1. A gauge for indicating the length of a valve lifter to be used to gauge a valve for an engine, comprising a hollow body having upper and lower ends, a stem movable in the lower end of the hollow body and protruding therefrom to cooperate with the lifting cam of the valve assembly, an indicator mounted in the hollow body and carried by and movable with the stem, said hollow body having a valve seat at its upper end to receive the valve being gauged, said indicator having an actuating member beneath said valve seat, said valve when in said seat in the hollow body engaging and operating the actuating member to indicate the length of the valve lifter to be used with that valve when in position in the engine.

2. A construction as defined in claim 1, wherein the exterior of hollow body is provided with a face to accurately fit and cooperate with the engine valve seat to receive the valve being gauged and wherein the hollow body below the valve seat engaging portion is reduced to extend through and be guided in the engine valve guide for the valve being gauged.

3. A construction as defined in claim 1, wherein the upper end of the hollow body is formed with an adjustable extension formed at the upper end with a seat for the valve being gauged.

4. A valve clearance gauge comprising a hollow tubular body, provided with a hollow extension stem extending from the said body a bevelled surface between the hollow body and hollow extension to fit in the valve seat of the motor, a movable plunger mounted within the stem and extending slightly beyond the stem, a clearance indicator gauge having a gauge plunger and mounted to the upper end of the stem and within the hollow body above the bevelled surface, a valve seat formed in the upper part of the body for receiving a valve, the stem of which rests upon the gauge plunger, the gauge reading indicating the length of valve lifter required when the valve is forced down on the valve seat of the body.
